UNITED STATES PATENT OFFICE.

JAMES T. PIGGOTT, OF PARKERSBURG, WEST VIRGINIA.

WINDOW-CLEANER.

1,348,443.

Specification of Letters Patent. Patented Aug. 3, 1920.

Application filed June 9, 1919. Serial No. 302,762.

To all whom it may concern:

Be it known that I, JAMES T. PIGGOTT, a citizen of the United States, residing at Parkersburg, in the county of Wood and 5 State of West Virginia, have invented certain new and useful Improvements in Window-Cleaners; and I do declare the following to be a full, clear, and exact description of the invention, such as will enable others 10 skilled in the art to which it appertains to make and use the same.

This invention relates to window cleaners, and more specifically to the class of window cleaners which are attached to or adjacent 15 to the front window of a street car or other conveyance for wiping snow, moisture, etc., from the window, so as to render the transparency of a window as nearly perfect as possible.

20 One object of this invention is to provide an improved window-cleaning attachment which may be quickly and easily attached to window sashes or frames of different sizes.

25 Another object is to provide an improved device of this character which consists of very few and comparatively inexpensive parts, and which is strong, durable and thoroughly practical.

30 Another object is to provide an improved device of this character in which the wiping member effects the wiping operation while moving in each of two opposite directions.

Other objects and advantages may become 35 apparent to persons who read the following details of description in connection with the accompanying drawings, in which:—

Figure 1 is a front elevation illustrating the general arrangement of parts in connection with a window frame.

40 Fig. 2 is a vertical sectional view, the section being taken substantially along line 2—2 of Fig. 1.

Fig. 3 is a detail in vertical section, the 45 section being taken substantially along the line 3—3 of Fig. 1.

Fig. 4 is an end view of the wiping member or plate detached from all other elements of the device.

50 Referring to these drawings in detail, in which similar reference characters correspond with similar parts throughout the several views, and in which a window frame 3 and window pane 4 may be of any well known construction,—

My improved attachment comprises a

pair of guides or guide rods 5, fulcrum members 6, a pivot rod 7, a wiping member 8, combined levers and counterweights 9 and an actuating or lifting element 10. 60

In order that this device may be quickly and easily attached to window sashes or frames of different types, one end of each rod 5 may be flattened and apertured for receiving screws 11 for securing this end of each rod to the window. A pair of brackets 12 are secured at convenient positions on the window, and each of these brackets is provided with an aperture 13 through which one of the rods 5 extends, the amount of extension being inversely proportional to the height of the window, it being understood that the rods 5 are slidable longitudinally in the apertures 13, and it should also be understood that the rods 5 may turn in the 70

apertures 13, so that the upturned apertured flanges of the brackets may be secured to the window in a plane different from that in which the lower flattened ends of the rods 5 lie. This feature of the invention 75

provides for a wide range of adjustment in attaching the device to windows of different sizes and shapes. Moreover, the pivot rod 7 may be sufficiently long for use in connection with the maximum width or horizontal 80

extent of windows to which a device of this character will be attached, and the same is true of the wiping member or bar 8. It should be understood, in this connection, that the wiping member 8 comprises a V-bar having 85

wiping-strips or edges 14 secured thereto by any appropriate means, and that the wiping bar is formed of a single relatively thin blank of sheet metal bent along its longitudinal center to form a tubular bearing 15. Therefore, when it is desired to 90

attach one of these improved window-cleaning devices to a narrow window, the length of the wiping member 14 may be reduced by cutting or sawing off the ends, and one 95

or both ends of the rod 7 may be cut off proportionally if desirable. The pivot rod 7 may be anchored either to the tubular bearing 15 or to one of the fulcrum members 6 by any appropriate means (not shown), so 100

as to prevent displacement of this pivot rod. Each fulcrum member 6 is preferably 105

formed integrally and consists of two tubular elements crossing one another at right angles, but the hollow portions being offset 110 from one another so that the pivot rods will not interfere with free movement of

the fulcrum member along the rod 5 on which it is mounted to slide. Each counterweight 9 is in the form of an arm which extends radially from the opposite side of the bearing 15 from the flanges which carry the wiping strips 14, and the flexible actuating element or cable 10 has its ends secured to the respective weights 9. The middle portion of the cable 10 constitutes a handle, and the portions between the middle and ends of the cable pass through openings in the window sash or frame, appropriate eyelets 16 being seated in these openings and surrounding the portion of the cable which extends through the sash or frame.

In operating this improved window-cleaning device, assuming that the wiping member is at its lowermost position, the middle portion of the cable 10 is grasped and pulled so as to draw the wiping member upward along the guides 5. Before starting upward, however, the pull of the cable 10 overcomes the counterweights, and the upper wiping edge or strip 14 moves downward and inward against the window pane, and therefore, it will be seen that the actuating element 10 effects pressing of the wiping member against the window while effecting the upward movement of the wiping member along the guides 5. When the actuating element 10 is released, the combined levers and counterweights 9 overbalance the wiping bar and cause its lower wiping edge 14 to press against the window and at the same time, the weights 8 facilitate the downward movement of the wiping member along the guides 5.

Although I have described this embodiment of my invention very specifically, it is not intended to limit this invention to these exact details of construction and arrangement, but changes may be made within the scope of the inventive ideas, as described and claimed herein.

What I claim as my invention is:—

1. In a window cleaner, a member comprising a V-bar formed of a single strip of sheet metal and including a tubular pivot-bearing extending along the apex of its meeting sides, wiping elements at the free edges of said member, a counterweight secured to and extending radially from the said tubular bearing, means to slidably mount the member in operative relation to a window, and means for imparting movement to the member.

2. In a window cleaner, a pair of guides, a pair of fulcrum members mounted for

movement along said guides adjacent to a window, a fulcrum-rod extended through said fulcrum members and fixed thereto, a wiping member fulcrumed on said fulcrum-rod and comprising upper and lower wiping edges, a combined lever and weight fixed to and extending radially from said wiping member at the opposite side of its fulcrum from said wiping edges and being effective to overbalance said wiping edges and press the lower one of said wiping edges against the window while facilitating the descent of the wiping member, and a lifting cable engaged with said combined lever and weight and being operatable to lift the latter and coöperate therewith to press the upper wiping edge against the window while lifting the wiping member.

3. In a window cleaner, a pair of upright guides, a pair of fulcrum members mounted for movement along said guides adjacent to a window, a fulcrum-rod extending through said fulcrum members and fixed thereto, a wiping member comprising a V-bar including a tubular pivot bearing extending along the apex formed by its meeting sides, said fulcrum-rod extending through said pivot bearing and constituting the pivot about which said wiping member is turnable, said wiping member comprising upper and lower wiping edges, a combined lever and weight fixed to and extending radially from said wiping member at the opposite side of its fulcrum from said wiping edges and being effective to overbalance said wiping edges and press the lower one of said wiping edges against the window while facilitating the descent of the wiping edges, a lifting cable engaged with said combined lever and weight and being operatable to lift the latter and coöperate therewith to press the upper wiping edge against the window while lifting the wiping member.

4. In a window cleaner, a member having a bearing sleeve and arms extending therefrom in diverging relation, wiping elements carried by said arms, a counterweight extending radially from said sleeve, a slidably mounted pivot rod extending through the sleeve and slidably and pivotally mounting the member in operative relation to a window, and flexible means connected with the counterweight and extended for passage through an opening to the opposite side of a window from said member.

In testimony whereof I have hereunto set my hand.

JAMES T. PIGGOTT.
